CANOPY

Lisa Sewell, 145 W. 87th St., and Lawrence E. Charity,
10 W. 90th St., both of New York, N.Y. 10024

Filed May 27, 1968, Ser. No. 12,087

Term of patent 14 years

Int. Cl. D25—02

U.S. Cl. D88—3

FIG. 1 is a perspective view of our design for a canopy for providing shade;

FIG. 2 is an elevational view of the canopy;

FIG. 2 is a plan view of the canopy;

FIG. 4 is a sectional view of one of the canopies, taken in the plane indicated by line 4—4 in FIG. 3; and

FIG. 5 is a view of the base of the canopy as seen in the plane indicated by line 5—5 in FIG. 2.

We claim:

The ornamental design for a canopy, substantially as shown.
